UNITED STATES PATENT OFFICE.

BENJAMIN W. HALL, OF HOLYOKE, MASSACHUSETTS.

DESIGN FOR A JOURNAL FOR LAY-BOYS.

SPECIFICATION forming part of Design No. 31,507, dated September 12, 1899.

Application filed August 5, 1899. Serial No. 726,348. Term of patent 14 years.

To all whom it may concern:

Be it known that I, BENJAMIN W. HALL, a citizen of the United States of America, and a resident of Holyoke, in the county of Hampden and State of Massachusetts, have invented and produced a new and original Design for a Journal for Lay-Boys, of which the following is a full, clear, and exact description.

This design relates to a peculiar and distinctive formation or contour of the base portion of the journal for a lay-boy more particularly, and is fully and clearly shown in the accompanying drawings, in which—

Figure 1 is a perspective view of the journal-box. Fig. 2 is a plan view, and Fig. 3 is an end view.

The leading characteristic of the design consists in the base A of the box, having the under side thereof concave, as shown at *a*, the said concavity extending from end to end of the base. The top of the base is flat, as indicated at *b*, and has intermediately extending beyond its opposite edges the wings *d d*, the edges of which are straight and parallel with

each other and also with the edge portions *d²* 25 *d²* of the base proper and are merged into said edge portions *d²* by the curves *f f*, as shown.

Rising above the top of the intermediate part of the base A is the member B, which constitutes the journal, the same having the 30 circular hole *g* longitudinally therethrough, and the top of the upstanding journal B is semicylindrical, as shown at *h*, being continued downwardly in the opposite flat sides to the top of the base.

Depending below the concave base of the lay-boy journal-box are the several prongs *h* 35 *h*, which are of an oblated conoidal form.

Having described my invention, what I claim as new, and desire to secure by Letters 40 Patent, is—

The design for a journal for lay-boys, substantially as herein shown and described.

BENJAMIN W. HALL.
